UNITED STATES PATENT OFFICE

2,610,533

DEFLECTOR FOR CONTINUOUS MILL

Gust S. Rask, Duluth, Minn.

Application September 8, 1949, Serial No. 114,480

1 Claim. (Cl. 80—51)

1

This invention relates to a deflector for a continuous mill and in particular to a deflector for deflecting bars out of the pass line of a continuous roughing mill.

In a roughing mill, which consists of a number of roll stands arranged in tandem, the billets or bars are fed into the first roughing mill in fairly close succession, so that there are several bars in the roughing mill at the same time. At times a bar passing through the mill will cobble up in one of the stands and can not be removed before the next succeeding bar reaches the cobbled bar. When this occurs considerable damage will occur to the guides and rolls. Also it makes it very difficult to remove the cobbled bars so that a long shut down period is required to remove the bars and start the mill in operation.

It is therefore an object of my invention to prevent more than one bar from cobbling at the same time.

Another object is to decrease the amount of damage done to the rolls and guides.

These and other objects will become apparent after referring to the following description and attached drawings in which:

Figure 1 is a top plan view of my device;

Figure 2 is a side elevation of Figure 1 showing a bar passing through the mill;

Figure 3 is a view similar to Figure 2, but showing a bar being deflected from the pass line;

Figure 4 is a sectional view taken on the line IV—IV of Figure 2;

Figure 5 is a sectional view taken on the line V—V of Figure 3; and

Figure 6 is a view of a release rod which forms part of my device.

Referring more particularly to the drawings the reference numeral 2 indicates one of the roll stands of a continuous bar mill. Such mills may have about nine stands, the stand indicated by numeral 2 being stand number 3. Spaced from the roll stand 2 is a second roll stand 4. A bar or billet B being rolled passes through the rolls of stand 2 through a bell guide 6 to the rolls of stand 4. Extending from the roll stand 2 to the bell guide 6 beneath the path of travel of bar B is a channel member 8 which is preferably attached to the housing of roll stand 2. A deflector chute 10 which is also located between the roll stands 2 and 4 is provided with a notched-out portion 12 at one end for receiving a fulcrum plate 14, this latter being attached to the housing of roll stand 4. The other end of the deflector chute 10 is normally suspended above the roll pass from a cross beam 16 which extends between the roll stands 2 and 4 and is supported thereby. In order to provide clearance for the bars B the beam 16 is arranged at an angle as shown. Clearance can also be provided by using two spaced apart beams. Extending around the 60

5 beam 16 and supported thereby is a chain 18, the ends of which extend below the deflector 10. A release rod 20 extends through a link in each end of the chain beneath the deflector 10 to support the deflector.

The operation of the device is as follows:

When a cobble occurs in a bar B after it has passed through the rolls of roll stand 4, the operator will pull the release rod 20 from the chain 18, thus permitting the end of the deflector 10 to drop to the beam 8 as shown in Figure 3. The succeeding bars, instead of passing through the roll stand 4, will be deflected upwardly away from the roll stand 4 as shown in Figure 3. This prevents further cobbling in the mill and enables the succeeding bars to be removed easily by the mill crane. If desired additional deflectors can be placed between other roll stands.

While one embodiment of my invention has been shown and described, it will be apparent that other adaptations and modifications may be made without departing from the scope of the following claim.

I claim:

25 A continuous rolling mill for rolling elongated articles including a pair of roll stands arranged in tandem and a deflector between said roll stands; said deflector comprising an elongated deflector chute located between the roll stands, means for pivotally supporting the end of the chute adjacent the second of said roll stands and above the roll pass, a beam beneath the pass line, a beam above the pass line, means suspended from the last named beam for releasably supporting the other end of the deflector chute above the roll pass, said last named means being adapted to release the said second end of the chute allowing it to drop to the first named beam and position it in the path of the moving object, the length of said deflector being so proportioned and the pivotal means for the first end of the chute being so positioned that the deflector in its dropped position will deflect the object above the adjacent side of the second stand and prevent entry into the pass thereof.

GUST S. RASK.
